UNITED STATES PATENT OFFICE.

MARK NOBLE, OF LANSING, WEST VIRGINIA.

RAIL-JOINT.

1,173,848.

Specification of Letters Patent. Patented Feb. 29, 1916.

Application filed June 18, 1915. Serial No. 34,900.

To all whom it may concern:

Be it known that I, MARK NOBLE, a citizen of the United States, residing at Lansing, in the county of Fayette and State of West Virginia, have invented new and useful Improvements in Rail-Joints, of which the following is a specification.

The present invention relates to improvements in means for connecting the meeting 10 ends of railway rails, and one of the objects of the invention is to provide a rail joint wherein the friction elements will so contact with the opposite faces of the rails as to retain the same in proper alinement and 15 to insure the rails against creeping, vertical or lateral movement.

A further object of the invention is to provide a chair upon which the meeting 20 ends of two rails rest and to construct the said chair so that the pressure or stress delivered from the rolling stock in passing the joint will cause the chair to more tightly 25 contact with the rails and hold the same in perfect alinement and in a rigid condition.

25 A still further object of the invention is to produce a rail joint which includes a chair upon which the rails rest, and to provide the chair with pockets within which are arranged friction members which are 30 forced into engagement with the opposite sides of the rail to hold the rails upon the chair, to obviate the necessity of providing the webs of the rails with the ordinary bolt 35 openings which tend to weaken the same, and further associate the friction members with a bond so that an electric connection 40 will be maintained between the rails.

A still further object of the invention is to provide a novel construction of rail 45 chairs having pockets receiving rail engaging friction members, said pockets being further provided with slideable members contacting with friction members to retain the last mentioned members in engaging position with the rail and to further provide adjusting elements for the slideable members which are so associated therewith as to effectively maintain the said sliding members within the pockets, and also to protect the 50 heads of the adjusting members by arranging the same between suitable ribs formed upon the outer faces of the chair.

With the above and other objects in view, the improvement resides in the construction, 55 combination and arrangement of parts set

forth in the following specification and falling within the scope of the appended claims.

In the drawings: Figure 1 is a side elevation of two rails connected in accordance with the present invention, Fig. 2 is a top 60 plan view of the same, Fig. 3 is a transverse section approximately on the line 3—3 of Fig. 1, Fig. 4 is a horizontal sectional view approximately on the line 4—4 of Fig. 1, Fig. 5 is a perspective view of the chair, 65 and Fig. 6 is a similar view of one of the rail engaging members associated with the chair.

Referring now to the drawings in detail, 70 1—1 designate two rails of the ordinary construction which have their ends abutting. In the present instance the rail ends do not have their webs provided with the usual bolt openings which, as is well known, have a tendency to weaken the same at 75 the points thereof requiring the greatest strength; that is, adjacent their ends.

The chair 2 includes a base 4 which is 80 preferably centrally formed with a longitudinal groove 5 which extends the entire length of the chair.

By reference to the drawings and especially to Fig. 3 thereof it will be noted that the base 4 is concaved longitudinally upon its undersurface, and thus it will be noted 85 that the base, while not weakened to any dangerous degree is of a less thickness at the central portion thereof than at any other point throughout its cross sectional diameter. This arrangement permits of a certain 90 and desired amount of resiliency of the central portion of the base, so that when a rail is received thereon and pressure, incident to the weight of the rolling stock passing thereover, is delivered centrally of the said base, 95 the same will be subject to a limited central downward pressure which will cause the side members to be forced more compactly against the sides of the rails as will, it is thought, be readily understood.

The base 4 is channeled horizontally in 100 opposite directions from the longitudinal walls provided by the channel 5, the said channels agreeing with the cross sectional shape of the flanges of the rails 1, and the lower horizontal portions of said channels are indicated by the numerals 7, while the upper or inclined walls which overlie the base flanges of the said rails 1 are indicated by the numeral 7¹, the inclined walls 7 110

having terminal and vertical walls 8 which are received in the fishing spaces of the said rails 1.

The outer faces, or the faces opposite those engaging the webs of the rails are beveled downwardly and outwardly from their upper horizontal edges toward the opposite longitudinal edges of the base proper, as indicated by the numerals 9, thus materially reinforcing both the vertical and the inclined walls 8 and 7 respectively. The base at the ends thereof is integrally formed with curved angular brace ribs 10 and the chair, at equal distances from the inner surface of the brace ribs 10 is provided with vertically extending longitudinally arranged enlarged portions 11, the upper surfaces of which being flush with the upper edges of the vertical walls 8, and the said enlarged portions project from the outer beveled surfaces 9 to the longitudinal edges of the chair. Each of the enlarged portions 11 is formed with preferably rectangular depressions providing each of said enlargements with pockets 12—12 separated by a central partition 13. The pockets open through the vertical walls 8 and as a consequence communicate with the rail receiving space in the chair, but the said openings are bridged by the upper edges of said vertical walls 8. The rear walls of the enlargements are each provided centrally of each of the depressions 12 with a vertical depression or channel 14, and the rear walls of the pockets central of each of the depressions 14 are formed each with a threaded opening 15. Engaging with the threads of each of the openings 15 are the shanks 16 of headed members 17. The heads of said members are received between the walls of the depressions 14, so that an obstacle cannot contact with the said heads, unless the same is of a size to be received within the channel 14.

The numerals 18 indicate what I term follower or locking blocks, one of which being snugly received within each of the pockets 12, and the rear wall of each of said locking blocks is provided with a circular opening 19 within each of which is arranged the end of one of the shanks 16 of the respective headed members 17. The bore of the orifice or opening 19 is non-threaded and is of a size sufficient to snugly receive the shank 17 without interfering with the threads thereof, and, of course, the shanks are adapted to contact with the inner walls provided by the said openings or depressions 19 in order that the blocks may be moved longitudinally toward the open faces of the pockets, which, for convenience, are indicated by numerals 20. The inner ends of the follower and locking blocks 18 are formed each with a substantially semi-cylindrical depression 21 and the periphery of

the said depression is provided with extending teeth 22. The teeth 22 are adapted to co-act with the teeth 23 provided upon the inner or rear face of friction members 24. These friction members are preferably in the nature of a cylindrical block and their outer faces or their faces not provided with the teeth 23 are roughened or serrated, as at 25. Also the portions of the friction members provided with the serrations 25 are of a greater radius than the inner portions of said members, or the portions thereof provided with the teeth 23, as indicated by the numeral 26, and while such an arrangement is not essential, it is found desirable to provide one of the sides of said friction members with a greater width than the other in order that the widened end will have a cam-like engagement between the walls of the depressions 21 and the lower walls of the pockets and so effectively sustain the said friction members within the pockets. The friction members are adapted to have their serrated faces forced into tight contact with the opposite sides of the webs of the rails and so provide means for preventing the longitudinal movement of the rails or the creeping thereof.

By reference to the drawings it will be noted that the arcuate toothed ends of the blocks 18 are not concentric with the toothed surface of the friction members 24, but are struck at a greater arc, and so it will be noted that the teeth of the friction members may be arranged between the teeth of the follower blocks either at the center or to the sides of the blocks, whereby the serrated faces of said friction members may be advanced toward or brought away from the webs of the rails without necessitating a great amount of adjustment of the members 17, and also whereby different portions of the serrated faces of the members 24 may be brought into engagement with the webs of the rails, should any portion of said serrated faces be subjected to wear.

The friction members are preferably centrally formed with openings 27, and the said openings are adapted to receive the opposite bent ends of conducting wires 28, the said wires being also received in suitable openings or depressions 29 in the partitions 13 between the respective pockets 12—12, and as the friction members are constructed of some hardened but electric conducting material it will be noted that the wire 28 provides an electric bond between each pair of friction members and consequently between the rails. In order to retain the angular ends of the wire 28 within the openings in the friction members, suitable sleeves of compressible but electric conducting material, such as lead or Babbitt metal, indicated by the numerals 30, may be arranged upon the wires and

forced in the said openings, or other suitable means may be employed for holding the bonds upon the friction members.

The longitudinal edges of the chair are 5 provided preferably between the brace ribs and the ends of the enlarged portions 11 with slots for the reception of the securing spikes 31 which enter the ties 3 and the heads of the spikes overlie the edges of the 10 base portion of the chair to the opposite sides of the central enlargements thereof, insuring the chair against longitudinal as well as lateral movement. Further, if desired, the base from the lower wall provided 15 by the groove 5 may be gradually increased in thickness to the mentioned longitudinal edges of the chair, so that the central portion of the chair will thus be rendered more resilient and the weight of the rolling stock 20 upon the rails received in the chair will have a greater tendency to force the walls 8 into tight engagement with the webs as well as beneath the underfaces of the heads of the rails.

25 From the above description, taken in connection with the accompanying drawings, the simplicity of the device, as well as the advantages thereof will, it is thought, be perfectly apparent to those skilled in the 30 art to which such invention appertains without further detailed description.

Having thus described the inventions, what I claim is:

1. In a means for connecting the meeting 35 ends of railway rails, friction members having serrated faces contacting with the webs of the rails, said friction members being provided with teeth, a follower member also provided with teeth co-engaging with 40 the teeth of the friction member, and an adjusting member for the follower member.

2. In a means for connecting the meeting 45 ends of railway rails, cross sectionally round friction members having one of their faces serrated, and contacting with the webs of the rails, the opposite faces of said members being formed with teeth, follower members each having one of its ends provided with a substantially semi-cylindrical 50 depression, the periphery of the said depression being formed with teeth, said teeth co-acting with the teeth of the follower member, and means for adjusting the follower member with relation to the friction member.

3. In a means for connecting the meeting ends of rails, a chair having a rail passage within which the rails are arranged, the walls of said passage contacting with the base, the web, and underlying the heads of 60 the rails, said chair being provided upon its upper face and upon each of its opposite sides with a pair of spaced pockets having openings which communicate with the rail receiving space of the chair, the outer wall 65 of each of the pockets being centrally provided with a depression and having threaded openings which enter the said depressions, a threaded member within each of the openings and having its head received within the depression, a friction member within each of the pockets, a follower member within each of the pockets and contacting with the friction member, and said follower members having one end 70 provided with an opening to receive the ends of the threaded members to permit of said threaded members contacting with the inner wall of each of said openings to force the follower into contact with the friction 75 member and to force each of said friction members into engagement with the webs of the rails.

4. In a means for connecting the meeting ends of rails, a chair having a rail receiving passage, said chair having its sides centrally provided with pockets having openings communicating with the rails, the outer walls of the pockets being formed with vertical depressions and having lateral 85 threaded openings which enter the pockets, a threaded member for each of the openings having its head received one within each of the depressions, a follower member contacting one with each of the side walls of 90 the pockets adapted to be adjusted longitudinally by one of said members, each of said follower members having its inner face 95 arcuate, and a rounded friction member within each of the pockets and engaged by each of the followers and adapted to be forced by the said followers into frictional engagement with the webs of the rails.

In testimony whereof I affix my signature in presence of two witnesses.

MARK NOBLE.
